POCKET COMB

Cecil H. Taylor, Kansas City, Mo.

Application October 21, 1946, Serial No. 704,610

4 Claims. (Cl. 132—15)

1

This invention relates to improvements in pocket combs and has particular reference to a hinged sectional comb. The application is a continuation in part of my application Serial No. 672,073, filed May 24, 1946.

The principal object of the present invention is the provision of a pocket comb having a pair of interhinged sections each section having a sheath or pocket to receive an integral portion of the other section whereby the parts are rigidly secured in alignment in both the opened and closed position.

Another object of the invention is the provision of a pocket comb having a pair of identically shaped inter-hinged toothed sections each having a sheath or pocket to receive the toothed portion of the other section when the comb is closed.

Another object is the provision of a folding comb having a pair of interhinged sections, each section having a pocket each provided at its inner portion with projections adapted to be inserted into the adjacent pocket when the comb is in the open position.

A further object is to produce a folding comb consisting of two sections which are identical so that if it is desired, as is preferred, to make the device out of plastic or other moldable material, both sections can be cast in the same die, thus effecting a considerable manufacturing economy.

Other objects are simplicity and sturdiness of construction, compactness of structure, ease and efficiency of operation, and adaptability for use in the various sizes and shapes of combs.

With these objects in view, as well as other objects, which will appear during the course of the specification, reference will be had to the drawing wherein:

Figure 1 is a side elevational view of a comb shown in the closed position and embodying this invention.

Fig. 2 is an end elevation of the comb.

Fig. 3 is an elevational view of the other end of the comb.

Fig. 4 is a side elevational view of the comb shown in the open position.

Fig. 5 is an edge view of the comb shown in the open position.

Fig. 6 is an enlarged sectional view taken on line VI—VI of Figure 4.

Fig. 7 is an enlarged fragmentary view of the end portions of the two sections shown in spaced apart relation.

Fig. 8 is an enlarged inner end view of one of the comb sections.

Throughout the several views, like reference

2

characters refer to similar parts and the numeral 10 designates the entirety of a folding comb having like sections 12 and 14. Each section is made of a single piece of material such as plastic, metal, etc., made by molding, casting or forming. Section 12 is provided with spaced apart side walls 16 and 18 joined together by top wall 20 and end wall 22 to form a sheath or pocket 24. Side wall 18 extends outwardly beyond side wall 16 and is notched at 26 to form a series of like comb teeth 28. It will be noted that pocket 24 is open at its bottom and at its inner end. Side wall 16 is provided with a projecting ear 30 having a socket in the form of a circular hole 32 formed therethrough with its center in alignment with the lower edge of wall 16. Side wall 18 also has a projecting ear 34 having a trunnion 36 disposed in axial alignment with hole 32 and extended outwardly to enter the socket of the other comb section as hereinafter described.

Comb section 14 comprises side walls 38 and 40 joined together at their top edges by top 42 and at their ends by end wall 44 to form a sheath or pocket 46 open at its bottom and at its inner end. Side wall 40 is notched at 48 to form comb teeth 50. These side walls 38 and 40 have projecting ears 51 and 52 respectively corresponding with the ears of section 12. Ear 51 is perforated at 54 to provide a socket and ear 52 has an outturned trunnion 56. It will be noted that these sections 12 and 14 are identical in shape and size, are interchangeable and can be produced in the same mold.

The ears having the pivoting means provided by the cooperating trunnions and sockets are positioned at the inner open ends of the sections and are adapted to be sprung apart to interfit the trunnion of each section with the socket of the other section and then be snapped back to position, whereby the two sections are hingedly joined together.

The top walls 20 and 42 are so positioned that when the comb sections are in the fully opened position they will be disposed end to end and will contact each other to prevent the opening of the sections beyond 180 degrees. This will insure the desired longitudinal alignment of the sections to present a comb body having the free ends of the teeth all disposed in substantially the same plane.

When it is desired to close the comb the sections are moved on their hinge from the open position until the comb teeth 28 are in pocket 46 and teeth 50 are in pocket 24. When thus closed the outer edges of sections 12 and 14 will be in

parallel relation and the comb teeth will be completely covered.

The adjacent faces of the two sets of comb teeth are in substantially planar relation so that when they are in the open position, as shown in Figure 6, they will have their points in substantially a straight line. It will be noted that each set of teeth is sharpened inwardly toward the center of the comb; furthermore, it will be noted that the two comb sections are so spaced that the teeth thereof will form a continuous row of equally spaced apart teeth when the comb is opened.

An important feature of the present comb is the enlargement of each of the ears 30 and 34 of section 12, and of each of the ears 51 and 52 of section 14, in more or less the manner shown at 60 for the ears 30 and 34 and at 62 for the ears 51 and 52, so that the enlarged ears will overlap and interfit adjacent to the bottoms of the side walls when the sections are folded as in Fig. 1 and adjacent to both the bottoms and tops of the side walls when the sections are extended as in Fig. 4. In this way the assembly is strengthened and rigidified and kept from bending and breaking when subjected to torsional or opposite side-wise stresses, particularly when the sections are in extended relation. It will be noted that each ear, including its enlargement, is identical with each other ear in respect of outline shape, i. e., in respect of its outer configuration as viewed in side elevation; see Fig. 4 and Fig. 7; so that they cooperate to provide the desired overlapping and consequent strengthening at the tops and bottoms of the side walls, where this relationship and this quality are needed, whether or not the ears are overlapped in the intermediate zone between the tops and bottoms.

While the trunnions 36 and 56 extend through the respective holes 54 and 32 and will serve to form a hinge between the two comb sections, yet it is found convenient in some instances to upset said trunnions whereby they overhang the edges of the respective holes to more securely fasten the parts against accidental separation. When the comb is made of metal the upsetting may be done by pressure and when plastic is used it may be accomplished by heat and pressure. The upsetting is best shown in Figure 6.

The comb structure just described presents a compact, sturdy and easily operated pocket comb, and one that has four smooth surfaces suitable for receiving printing or other advertising matter, that are always exposed whether the comb is open or closed.

What I claim as new and desire to protect by Letters Patent is:

1. A folding comb comprising a pair of identical sections each including a pair of spaced apart side walls integrally connected along their top edges and along one end edge to provide a pocket open at its bottom and at one end, comb teeth projecting from one of said side walls and each tooth having a length less than the depth of the pocket, and means pivoting the open ends of the two sections together with the teeth of each section aligned with the open bottom of the other section for movement from a folded position in which the teeth of each section are fully contained within the pocket of the other section to an extended position in which the sections are disposed end to end with the free ends of the teeth all disposed in substantially the same plane, said pivoting means comprising ears of identical outline

shape projecting endwise from each side wall at the open ends of the sections with adjacent ears of the respective sections overlapping each other adjacent to the bottoms of the side walls when the sections are folded and adjacent to the tops and bottoms of the side walls when the sections are extended in order to strengthen and rigidify the assembly.

2. A folding comb comprising a pair of identical sections each including a pair of spaced apart side walls integrally connected along their top edges and along one end edge to provide a pocket open at its bottom and at one end, comb teeth projecting from one of said side walls and each tooth having a length less than the depth of the pocket, and means pivoting the open ends of the two sections together with the teeth of each section aligned with the open bottom of the other section for movement from a folded position in which the teeth of each section are fully contained within the pocket of the other section to an extended position in which the sections are disposed end to end with the free ends of the teeth all disposed in substantially the same plane, said pivoting means comprising a trunnion laterally projecting from a side wall of each section adjacent to the open end and open bottom of the pocket thereof and a socket opening toward and aligned with said trunnion and formed in the other side wall of said section adjacent to the open end and open bottom of the pocket thereof, whereby the two sections are pivoted together by interfitting the open end portions of the respective side walls and positioning the trunnion of each section in the socket of the other section.

3. A folding comb comprising a pair of identical sections each including a pair of spaced apart side walls integrally connected along their top edges and along one end edge to provide a pocket open at its bottom and at one end, comb teeth projecting from one of said side walls and each tooth having a length less than the depth of the pocket, and means pivoting the open ends of the two sections together with the teeth of each section aligned with the open bottom of the other section for movement from a folded position in which the teeth of each section are fully contained within the pocket of the other section to an extended position in which the sections are disposed end to end with the free ends of the teeth all disposed in substantially the same plane, said pivoting means comprising a trunnion laterally projecting from a side wall of each section from which the comb teeth project, the trunnion being located adjacent to the open end and open bottom of the pocket in said section, and a socket opening toward and aligned with the trunnion, said socket being formed in the other side wall of said section and being located adjacent to the open end and open bottom of the pocket in said section, whereby the two sections are pivoted together by interfitting the open end portions of the respective side walls and positioning the trunnion of each section in the socket of the other section.

4. A folding comb comprising a pair of identical sections each including a pair of spaced apart side walls integrally connected along their top edges and along one end edge to provide a pocket open at its bottom and at one end, comb teeth projecting from one of said side walls and each tooth having a length less than the depth of the pocket, and means pivoting the open ends of the two sections together with the teeth of each section aligned with the open bottom of the other

section for movement from a folded position in which the teeth of each section are fully contained within the pocket of the other section to an extended position in which the sections are disposed end to end with the free ends of the teeth all disposed in substantially the same plane, said pivoting means comprising a trunnion projecting outwardly from a side wall of each section adjacent to the open end and open bottom of the pocket thereof and pivotally fitting into a hole provided through the other side wall of said section adjacent to the open end and open bottom of the pocket thereof.
